UNITED STATES PATENT OFFICE

129,203

DESIGN FOR A PAIR OF SUNGLASSES

William Huppert, New York, N. Y., assignor to
Fosgood Corporation, Leominster, Mass., a cor-
poration of Massachusetts

Application December 6, 1940, Serial No. 97,113

Term of patent 7 years

To all whom it may concern:

Be it known that I, William Huppert, a citizen of the United States and resident of New York city, in the county of New York and State of New York, have invented a new, original, and ornamental Design for a Pair of Sunglasses, of which the following is a specification, reference being had to the accompanying drawing, forming part thereof, in which:

Figure 1 is a front view of a pair of sunglasses showing my new design; and

Fig. 2 is a top plan view thereof.

My design for sunglasses, as shown, is characterized by the specific configuration of the upturned cusps at the outer ends of the lens rims, the same being in a plane substantially below the plane of the upper surfaces of the rim tops, in combination with lenses of an ovoid shape.

I claim:

The ornamental design for a pair of sunglasses, substantially as shown and described.

WILLIAM HUPPERT.
